UNITED STATES PATENT OFFICE.

LYMAN R. ROBERTS, OF RUTHERFORD, NEW JERSEY, ASSIGNOR TO UNDERWOOD TYPE-WRITER COMPANY, OF NEW YORK, N. Y., A CORPORATION OF DELAWARE.

TYPE-WRITING-MACHINE OPERATOR.

1,114,644.

Specification of Letters Patent.

Patented Oct. 20, 1914.

Application filed March 16, 1910. Serial No. 549,723.

To all whom it may concern:

Be it known that I, LYMAN R. ROBERTS, a citizen of the United States of America, residing in Rutherford, county of Bergen, and State of New Jersey, have invented certain new and useful Improvements in Type-Writing Machine Operators, of which the following is a specification.

This invention relates to power-driven key-controlled means for actuating the type-bars of writing machines, or such parts of other machines as have heretofore been customarily actuated directly by the keys.

According to the present invention, a key is depressed and a transmitter or interponent is shifted into the path of a power-driven rotary pin or driver, whereby the transmitter is driven; the transmitter being connected to the part which it is desired to operate by power, in the present instance the type-bar of the writing machine, although the invention is not limited thereto. After the rotary driver has carried the transmitter the desired distance, the latter is automatically released from the driver. This prevents further interference between the transmitter and the driver at that key-stroke. Even though the key is held down, there is no danger of the stroke of the type-bar or other part being repeated. Moreover the type-bar or other part may return toward normal position ahead of the return of the key to normal position. Upon releasing the key from pressure, the transmitter is returned to its normal position ready for another operation. There may be a single power-operated shaft or member extending along a series of keys, with transmitters in the form of latches, hooks or trips controlled by the keys, for connecting their respective type-bars or driven members with the common power shaft, in the described manner. There may be provided a device for tripping the latches or trips, and the same may be made adjustable so that the type-bars may be released at any desired point before striking, thereby to regulate the force of impact of the type-bars upon the platen.

In the drawings accompanying and forming a part of this specification, Figure 1 is a sectional side elevation of an "Underwood" typewriting machine, illustrating the type-bar action with my improvements applied thereto, the parts being shown in normal

positions. Fig. 2 is a fragmentary side elevation, showing a finger key depressed and the actuator as just engaging with the lever-latch. Fig. 3 is a similar view to Fig. 2, but illustrating the parts in the positions they assume just after the lever has been tripped by the actuator. Fig. 4 is a view similar to Fig. 2, but illustrating the finger key as being retained in its depressed position and the lever-latch locked out of the path of the actuator. Fig. 5 is a perspective view of a portion of the actuator.

Similar characters of reference designate like parts throughout the different views of the drawings.

In Fig. 1 I have shown in side elevation the type-bar action of the well-known "Underwood" typewriting machine, in which the type-bars 1 are pivotally mounted in a segment 2 and strike upwardly and rearwardly against the platen 3, the type-bar segment being provided with a type-bar guide 4. The type-bars have heels 5 which engage with a universal bar 6, common to all the type-bars, just before they strike the platen to operate escapement mechanism (not shown) to advance the platen carriage step-by-step in letter-feeding direction. Each of the type-bars has a bell-crank lever connection 7 with a pivoted operating lever 8, guided in a comb 9 for up and down reciprocatory movement. The connections between the type-bars, bell-cranks and operating levers are of the usual construction in said "Underwood" typewriting machine. Each of the operating levers has at its forward end a connection in the form of a pivoted latch 10 having a hook portion 11, to engage a trip on the power-operated member whereby the operating levers may be selectively connected for operation to the power member.

Selective mechanism is provided for operating the type-bar levers, comprising a series of depressible keys 12 secured to stems 13, the same as in the usual typewriter keyboard. The said keys are mounted for up and down reciprocatory movement in a pair of superposed bars 14, 15 extending across and fixed to the machine frame 16, the upward movement of said keys being limited by pins 17. Compression springs 18 coiled around the stems and confined between the lower bar 15 and the pins 17, return the keys to normal position.

The actuator consists of a power-driven shaft 18' rotatively mounted in the machine frame and extending transversely thereof near the forward ends of the levers 8, and 5 having at one end outside of the frame 16 a drive wheel or pulley 19, connected in any suitable manner to a source of power, in the present instance indicated as a belt 20' passing around said pulley 19 and connected to 10 a motor (not shown). Secured at intervals along said shaft 18' is a series of disks or wheels 20 through which passes a rod 21 to from trips to engage the latches 10 and pull them downward and thereby operate 15 the type-bar operating levers 8.

The operation is substantially as follows: Assuming the parts to be in the positions indicated in Fig. 1, the actuator continuously rotates in the direction of the arrow. 20 Upon one of the finger keys 12 of the selective mechanism being struck, the same as in the operation of the key-board of the usual typewriting machine, the stem 13 engages with a lip 22 on the connector or latch 10 and swings the latch on its pivot 23, so that the hook portion 11 projects into the path of the trip 21 (Fig. 2). The trip as it rotates engages the latch and exerts a downward pull upon the lever 8, throwing the 25 type-bar up against the platen. The actuator pulls the latch down until an inclined portion 24 on said latch engages with a universal let-off 25, in the form of a rod extending transversely of and adjustably secured in slots 25' in the machine frame 16. 30 The parts are now in the positions illustrated in full lines in Fig. 3. As soon as the trip is disengaged from the latch 10 said latch is moved out of the path of the actuator by a spring 26 and returned to the 35 normal position (Fig. 1) and held by said spring 26 in idle position against the stop bar 27 to prevent repeated engagement of the trip with the latch and the consequent 40 repeated operation of the type-bar.

To prevent repeated engagement of the latch by the trip, should the finger of the operator be accidentally or unconsciously left upon the key 12 after it has been depressed, I provide the latch with a pin 28 to coöperate with a stationary by-pass pin or ward 29 about which the pin 28 moves in an irregular orbit. The by-pass pins 29, one of which is provided for each latch, 50 may be supported on the machine frame in any convenient manner, as for example, by being secured to arms or standards 16' rising from the base of the machine frame. Should the operator's finger remain on the 55 depressed key, as already stated, after the coupler or latch has been tripped, the latch is snapped out of the path of the revolving actuator or driver by the spring 26, and into engagement with the stop bar 27. The 60 lever 8 and latch 10 move upward until the 65 lever 8 and latch 10 move upward until the

latch strikes the key stem 13 (Fig. 4), the pin 28 being brought by this movement to a position behind the by-pass pin 29. The latch 10 is held in this position, while the key 12 remains depressed, being prevented from farther upward movement by the stem 13, and from forward movement about its pivot by the pin 29.

It will be obvious that when the latch is tripped by the actuator a quick stroke may be imparted to the type-bar 1, the connection of the actuator with the latch being maintained until the type has reached or nearly reached the platen and a consequent powerful type impression made against the platen. While this powerful blow of the type against the platen is essential in some instances, as in doing manifold work a number of carbon sheets in addition to the usual sheets being in the machine, it would be a disadvantage when only a single sheet is to be written upon. To overcome this disadvantage I provide means for varying or regulating the degree of the type blow against the platen irrespective of whether the actuator is rotating at high or low speed. This is accomplished by the adjustment of the universal let-off 25. By adjusting said let-off to the right, it will be obvious that when the inclined portion 24 of the latch engages therewith and is thrown out of engagement with the trip 21, a downward pull of considerable extent will have been imparted to the type-bar operating lever 8 and a consequent heavy blow of the type against the platen. 90 However, should the let-off be adjusted to the left the latch 10 will be thrown out of engagement with the trip after only a slight downward pull is exerted upon the lever 8 and a consequent light blow of the type against the platen. 100

Variations may be resorted to within the scope of the invention, and portions of the improvements may be used without others.

Having thus described my invention, I claim:

1. In a typewriting machine, the combination with a power driven actuator, of a series of type-bar levers; latches pivoted to said levers and having hook portions; a fixed stop with which said latches normally engage; depressible finger keys having stems mounted for vertical movement and adapted to engage with the latches when depressed to throw the hook portions of the latches into the path of the actuator to be engaged thereby to operate the type-bars; a universal let-off which said latches engage to throw them out of engagement with the actuator; pins carried by said latches; fixed by-pass pins about which said latch pins move through their normal orbit of movement; and springs to return the latches to normal position against the fixed stop out of the path of the actuator.

2. In a typewriting machine, the combination with a power driven actuator, of a series of type-bars; type-bar levers; latches having hook portions and pivoted to said levers; keys having stems mounted for vertical movement and engaging with the latches to project them into the path of the actuator which engages with the hook portions of the latches to operate the type-bars; a bar with which said latches engage to throw them out of engagement with the actuator, said bar being adjustable to control the engagement of the latches with the actuator to regulate the pressure of the type-bar blow at the printing point; springs to return the latches to normal position; pins connected to said latches; and fixed by-pass pins about which said latch pins move through their normal orbit of movement, but with which they engage when the key remains depressed to hold the latches out of the path of the actuator to prevent repeated operation of the type-bars.

3. In a typewriting machine, the combination of type-bar levers; latches having hook portions and pivoted to the said levers; finger keys having vertically movable stems to engage with the latches to rock the same and project them forwardly; a power driven actuator comprising a shaft having a series of disks fixed thereon and spaced apart, and a rod passing through the disks parallel with the shaft to form trips to engage with the hook portions of the latches when the latter are projected forward and into the path of the actuator by the finger keys; and a universal let-off with which said latches engage to throw them out of engagement with the actuator.

4. In a typewriting machine, the combination with the type-bars, of levers connected thereto; latches having hook portions and pivoted to said levers; a power actuator comprising a shaft extending transversely of the levers with disks fixed thereon and spaced apart, and a rod passing through said disks parallel with the shaft to form a trip; depressible keys having stems to engage with and project the latches into the path of the actuator so that the trip will engage with the hook portions of the latches to operate the type-bars; pins carried by said latches; and fixed stop pins with which said latch pins engage to maintain said latches out of the path of the actuator when a key remains depressed after a type-bar has been actuated to prevent repeated operation of said type-bar.

5. In a typewriting machine, the combination with a series of pivotally supported type-bars, of fulcrumed levers connected to said type-bars; latches pivotally connected to said levers; a fixed stop; springs to normally maintain the latches in engagement with said stop; a power actuator extending

transversely of the levers; depressible finger keys having stems to engage with the latches to project them into the path of the actuator to operate the type-bars; an adjustable let-off with which the latches engage to throw them out of engagement with the actuator; and a series of fixed stops out of the normal path of the latches, but with which the latches engage when the finger keys remain depressed and in engagement with the latches to prevent repeated operation of the type-bars.

6. In a typewriting machine, the combination with a platen, of a type bar, a key lever below and operatively connected to said type bar; a latch on said key lever comprising a bell crank arm, a depressible key arranged to strike said arm and swing said latch, and a power driven device for striking said latch and thereby operating said key lever.

7. The combination of a constantly revolving driver, a type-operating device, a coupler pivoted to said type-operating device, a spring holding said coupler away from said constantly revolving driver, a key to swing said coupler on its pivot into the path of said driver, and thereby form a positive driving connection, positive means to disconnect the coupler from the driver, means to return the type-operating device and coupler, a projection on said coupler, and a ward on the framework to coöperate with said projection to prevent reengagement of the coupler and the driver while the key is held depressed.

8. The combination of a constantly revolving driver, a type-operating device, a coupler pivoted to said type-operating device, a spring holding said coupler away from said constantly revolving driver, a key to swing said coupler into the path of said driver, positive means to disconnect the coupler from the driver, means to return the type-operating device and coupler, a projection on said coupler, and a ward on the framework to coöperate with said projection to prevent reengagement of the coupler and the driver while the key is held depressed, said type-operating device and said coupler being constructed to rise together with said key and free said projection from said ward, whereby the coupler may move into engagement with the driver on the next depression of the key.

9. A coupler for use between a revolving driver and a type-operating device, comprising a key-driven arm, a hook, and an extension to engage with a releaser, said coupler having a projection for engagement with a ward to prevent repetition.

10. The combination of a constantly revolving driver, a lever, as 8, a coupler, as 10, a key to swing the coupler into the path of the driver, and positively connect

the driver and lever, positive means to trip the coupler away from the driver, and a by-pass or ward, as 29, to engage the coupler to prevent repetition while the key 5 is down:

11. The combination of a type-operating device, a power-driver, a key, a coupler movable by said key to positively connect the driver to the type-operating device,

10 means being provided to release the coupler from the driver, said key tending when held down to re-connect the coupler to the driver, and means opposing such tendency and preventing re-connection of the coupler 15 to the driver while the key is held down.

12. The combination of a type-operating device, a power-driver, a key, a coupler in the path of said key and movable by said key to connect the driver to the type-operating device, means being provided to release the coupler from the driver, said key tending when held down to re-connect 20 the coupler to the driver, means opposing such tendency and preventing the coupler 25 from being re-connected to the driver before the key has been returned, a spring to return the type-operating device and coupler, and a spring to return the key.

13. The combination of a depressible type-operating lever or device, a coupler 30 pendent therefrom, an arm on said coupler, a depressible key having a part to engage and depress said arm to swing said coupler, a revolving driver to be engaged by said 35 coupler, means to release the coupler, means to return the type-operating device and the coupler, means to return the key, and means to prevent reengagement of the coupler with the driver while the key is held down.

40 14. In a type-writing machine, the combination with type-bars, of levers connected thereto, latches pivoted to said levers and having hook portions, an actuator comprising a shaft extending transversely of the 45 levers, disks fixed thereon and spaced apart, and a rod passing through said disks parallel with the shaft to form a trip, depressible keys operable to engage and project the latches into the path of the actuator

50 so that the trip will engage with the hook portion of the latches to operate the type-bars, springs to return said latches to normal positions, and stops with which said latches engage when the keys remain depressed to maintain said latches out of the path of the actuator and prevent repeated 55 operation of the type-bars.

15. In a typewriting machine, the combination with a series of type-bars, of fulcrumed levers connected to said type-bars, bell crank latches pivotally connected to 60 said levers and each having a horizontally

disposed arm, a power actuator extending transversely of the levers, and depressible finger keys having stems to engage with the horizontal arms of the bell crank latches to project them into the path of the actuator to operate the type-bars.

16. In a typewriting machine, the combination with a series of pivotally supported type-bars, of fulcrumed levers connected to said type-bars, bell crank latches pivotally connected to said levers and each having a horizontally disposed arm, a fixed stop, springs to normally maintain the latches in engagement with said stop, a power actuator extending transversely of the levers, depressible finger keys having stems to engage with the horizontal arms of the bell crank latches to project them into the path of the actuator to operate the type-bars, and an adjustable let-off with which the latches engage to throw them out of engagement with the actuator.

17. The combination of a type-operating lever, a constantly revolving driver, a coupler connected to said lever and normally disconnected from said driver, a key to connect said coupler to said driver, positive means to disconnect the coupler from the driver, means to return the lever to an intermediate position in advance of the return of the key, and means operative while the lever is in said intermediate position to prevent reengagement of the coupler with the driver while the key is held depressed.

18. The combination of a constantly revolving driver, a type-operating device, a coupler pivoted to said type-operating device, a spring holding said coupler away from said constantly revolving driver, a key to swing said coupler on its pivot into the path of said driver and form a positive driving connection between the coupler and the type-operating device, means to disconnect the coupler from the driver, means to return the type-operating device and coupler, and means to detain the coupler out of the path of the driver while said key remains depressed.

19. The combination of a revolving driver, an arm to be driven, a coupler connected to said arm comprising a hook to engage the driver and form a positive driving connection for said arm, means to release said hook, a projection on said hook, and a ward to be engaged by said projection to prevent repeated operation of said arm.
